Primary Examiner—Stella Reid

[57] **CLAIM**

The ornamental design for a transcutaneous electrical nerve stimulator, as shown.

DESCRIPTION

FIG. 1 is a perspective view of a transcutaneous electrical nerve stimulator, showing my new design;
FIG. 2 is a side elevational view thereof;
FIG. 3 is a rear elevational view thereof; and
FIG. 4 is a side elevational view thereof, opposite that shown in **FIG. 2**.
